United States Patent

Des. 239,461
Patented Apr. 6, 1976

239,461

PACKAGING MACHINE

Larry W. Heavner, Glen Ellyn, and Kenneth L. Gidewall,
Clarendon Hills, Ill., assignors to Coronet Container
Corporation

Filed July 19, 1973, Ser. No. 380,671

Term of patent 14 years

Int. Cl. D15—99

U.S. CL. D55—1 C

FIG. 2.

FIG. 1.

FIG. 3.

FIG. 4.

FIG. 5.

FIG. 1 is an elevational view of one end of our packaging machine, particularly useful for vacuumizing and heat sealing commodities preferably in a controlled atmosphere;

FIG. 2 is a front elevational view of the embodiment of FIG. 1;

FIG. 3 is an elevational view of the other end of the embodiment of FIGS. 1 and 2;

FIG. 4 is a rear elevational view of the embodiment of FIGS. 1-3; and

FIG. 5 is a top plan view of the embodiment of FIGS. 1-4.

We claim:

The ornamental design for a packaging machine, substantially as shown.
